UNITED STATES PATENT OFFICE.

JOHN HENRY JENKINS, OF WACO, TEXAS.

GIN BRUSH.

Application filed June 15, 1925, Serial No. 37,307. Renewed August 13, 1926.

This invention relates to cotton gin brushes and more particularly to metal brushes of this character.

The object of the invention is to provide a brush of this character constructed to be strong and durable and yet permitted to be made of light weight metal, the wings or blades of which are constructed so as to avoid the cotton hanging or adhering to the edges thereof.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings:—

Figure 1 represents a perspective view of a gin brush constructed in accordance with this invention; and

Figure 2 is a detail transverse section through a portion thereof showing one of the blades.

In the embodiment illustrated the brush constituting this invention comprises a cylindrical body member 1 having disk-like heads 2 and 3 at its opposite ends, said heads projecting beyond the body of the brush and provided with journals as 4 provided for the mounting of the brush.

A plurality of metal strips or wings 5 extend longitudinally of the brush in peripherally spaced relation and are secured to the heads 2 and 3 by means of securing strips 10. These blades 5 extend radially from the brush and have right-angularly extending lateral flanges 6 at their inner edges over which the securing strips 10 are mounted as is shown clearly in Figure 2.

These blades or strips 5 have their outer edges turned inwardly and crimped as shown at 7 which in addition to providing smooth edges to prevent hanging of the cotton thereon increases the strength of the blades and permits them to be made of light weight metal to prevent the brush being excessively heavy.

It is of course known that these brushes revolve at high rates of speed in order that they may fan the cotton off the gin saws and this construction of blade adapts them to resist the air pressure incident to this rapid revolving of the brush.

This brush constructed as herein shown and described may be cheaply constructed, keeps the flues clean and gives general satisfaction.

I claim:—

A cotton gin brush having a plurality of radially extending blades, said blades having crimped unbroken outer edges.

In testimony that I claim the foregoing as my own, I have hereto affixed my signature.

JOHN HENRY JENKINS.
